Levi Peterson & Peter Peterson

Letters Patent, dated 29 May 1830

The schedule, referred to in these Letters Patent, and making part of the same, containing a description in the words of the said Levi Peterson & Peter Peterson themselves, of their improvement in the Baking Stove.

The subscribers wish to introduce to the publick their new improved baking stove for family use, steam boats, hotel &c &c. They vary in size to suit the purpose they are intended for, and can be made of either wrought- or cast iron. The stove made for family use is of cast iron, thirty inches long, twenty inches wide and twenty six inches high: in the top are three holes to receive the boilers. One of the broad sides being the front of the stove, it represents the oven, the fire place; and the ash pit; a convenient bench extends the whole length of the stove and twelve inches wide; the oven extends from within four inches of the top to within two inches of the bottom of the stove, forming a fire round the oven of two inches by twenty, being the width of the stove; the size of the oven is fourteen inches wide, eighteen inches high; and extends back twenty inches, the width of the stove; the fire place is at the one side of the oven, twelve inches wide and runs back the width of the stove, leaving a sufficient space for the ash pit and draft directly underneath.

The fire being at one side of the oven and near the top of the stove, the fire passes directly over the oven and the flue descends down the other side and continues underneath the oven and ash pit to the extreme end of the stove. From this advantage and application of the fire, this stove is heated thoroughly and equally on all parts.

The fire acts on the fire box which is in the top of the stove it then passes around the oven and underneath the ash pit where it runs into the pipe, consequently the whole effect of the fire is applied before it can possibly pass off into the pipe, which is a great saving of fuel &c &c.

important improvement.

Having described this cooking stove, we will now draw your attention to the advantages.

It is simple in the construction and not liable to get out of order - consumes very little fuel, will take up but little room, can be placed in any part of a room to suit convenience or saving of labour to the cook - and will do away the necessity of the principal cooking utensils used in a kitchen, inasmuch as this stove comprises every convenience necessary for cooking. Baking, roasting, boiling, steaming, stewing, frying and boiling, all can be done at the same time without any inconvenience, one to the other.
